FRANK KUSTERLE, OF KENOSHA, WISCONSIN, ASSIGNOR TO SIMMONS COMPANY, OF NEW YORK, N. Y., A CORPORATION OF DELAWARE

FURNITURE POST END CONSTRUCTION

Application filed December 12, 1929. Serial No. 413,441.

This invention relates to furniture post end construction and has particular reference to a structure for finishing off the end of a tubular metal or like post.

- 5 The objects of the invention are to provide an improved post end structure for eliminating sharp edges on the post end which might cut, scratch, or otherwise injure any finished surface upon which the post end might rest; 10 to provide a reinforced end structure which also improves the general appearance of the post; to provide an end trimming which can be cheaply and economically made and applied to the post end and when once applied is 15 practically permanently mounted on the post end; and in general, it is the object of my invention to provide an improved post end structure of the character above referred to.

Other objects and advantages of my invention will be understood by reference to the following specification and accompanying drawing in which I have illustrated three different forms of post end structure which embody the features of my invention.

25 In the drawing:

Fig. 1 is a vertical axial section through a round tubular metal post which is provided with an end fitting according to my invention.

30 Fig. 2 is a section on the line 2—2 of Fig. 1.

Fig. 3 is a vertical sectional view similar to Fig. 1 but showing my invention as applied to a post of generally rectangular cross-section.

35 Fig. 4 is a bottom end view of the structure shown in Fig. 3, the tip member being removed to more clearly illustrate the end trimming.

Fig. 5 is a section on the line 5—5 of Fig. 3, 40 with the tip member removed, and

Fig. 6 is a sectional view similar to a part of Fig. 1 but showing a slightly modified form of structure.

Referring now to Figs. 1 and 2 of the drawing, I have shown a round tubular metal post at 6, the lower end thereof being swaged outwardly or otherwise stretched and enlarged as indicated at 7. An end trimming or collar 8 is mounted on the enlarged end 7 of the post 6 and includes an outer flange or sleeve

part 9 which fits snugly around the said enlarged post end 7. The outer flange part 9 includes an upper end portion 10 which is of such diameter that it fits snugly about a portion of the post immediately adjacent the enlarged end portion 7. Obviously, the trimming member 8 can not be removed from the end of the post because of the outwardly flaring enlarged end of the post and the similarly shaped outer flange part 9 of the trimming, 55 and for preventing displacement of the trimming along the post, I provide an inwardly and upwardly turned flange part 11 which is folded around the lower end of the post so that the lower marginal portion of the latter 60 is enclosed between the outer and inner flange parts 9 and 11. Where the post is round as in Figs. 1 and 2, the inner flange 11 may conveniently be made continuous, and it will be seen that this inner flange anchors the trimming on the end of the post against displacement upwardly along the post. The folding of the trimming along the lower end of the post provides a smooth rounded lower end 65 surface 12 which will not readily scratch or otherwise injure any finished surface which the post might rest upon. One such finished surface might be the surface of a bakelite end fitting 13 which is provided with a spring retaining member 14, the latter being adapted 70 to yieldingly engage the opposite sides of the post to retain the end fitting in place when the post is lifted from the floor or other surface.

In Fig. 6, I have disclosed a slightly modified form of the structure shown in Figs. 1 and 2. In the said Fig. 6, the post is indicated at 15 and the end trimming at 16. Instead of folding the end trimming around the lower marginal portion of the enlarged 80 end of the post, the end trimming may be provided with an inwardly rebent lower marginal portion 17, the end 18 of which engages the lower end 19 of the post as clearly shown. Obviously, engagement of the ends 18 and 85 19 prevents displacement of the end trimming 16 upwardly along the post, while the outwardly flaring lower end of the post prevents endwise removal of the fitting. The lower end of the fitting 16 is provided with 90

a smooth rounded surface 20 which will not be apt to scratch a finished surface.

In Figs. 3, 4 and 5, I have disclosed my invention as applied to a more or less rectangular tubular post 21. The general cross-sectional shape of the post herein disclosed is clearly shown in Fig. 5, from an inspection of which it will be seen that two of the walls 22 and 23 are substantially flat, while the other two walls 24 and 25 are provided with outwardly bulged or rounded faces to form a more or less ornamental appearance. A trimming member 26 is provided for the lower end of the post 21, and the said lower end is enlarged by spreading outwardly the lower marginal portions of each of the walls. In so spreading or enlarging the lower end portion of the post, the tube is split at its four corners as indicated at 27.

The trimming member 26 consists of an outer flange or sleeve-like element, the upper portion 28 of which is shaped to fit snugly around the portion of the post immediately above the enlarged lower end portion thereof. Obviously, the closely fitting upper portion 28 of the trimming will prevent endwise removal of the post since the said portion 28 can not slide past the enlarged post end. The lower portion 29 of the trimming may conveniently be made of some other cross-sectional shape, for instance, rectangular as shown in Figs. 4 and 5 wherein all sides are substantially flat or straight. Thus an ornamental effect is provided on the lower end of the post.

As clearly shown in Figs. 3 and 4, the enlarged or spread lower end of the post fits snugly within the enlarged portion 29 of the trimming and for preventing displacement of the trimming upwardly along the post. The trimming is provided with ears or flanges 30 which are bent inwardly and upwardly inside of the enlarged post end so as to embrace the respective walls of the post as clearly shown. By this means, the trimming is anchored against displacement upwardly along the post. If it is desired to prevent the square cut bottom edge portions 31 of the trimming from engaging the surface on which the post rests, the ears 30 may be bent inwardly in such a manner that the incidentally formed smooth rounded end portions 32 will rest on the supporting surface which, in the present instance, is a shoulder 33 formed on a suitable bakelite or like tip member 34. The tip 34 is provided with a spring retaining means 35 which is adapted to yieldingly frictionally engage the inside walls of the post to normally hold the tip in place in the end of the post.

I am aware that the trimming structure above described may be changed in numerous details including the relative shape of the upper and lower portions thereof, and therefore do not wish to be limited to the precise

details disclosed but intend that the scope of my invention should be determined by reference to the following claims, which should be construed as broadly as possible consistent with the state of the art.

I claim as my invention:

1. A tubular furniture or like post having an end portion enlarged in cross-sectional dimension relative to the corresponding dimension of the adjacent portion of the post, and a self-retaining separate annular end trimming fitting snugly over and shaped longitudinally to conform to the shape of said enlarged post end and adjacent post portion, whereby said trimming is locked to the post against endwise removal from such post end, and an inturned flange part integral with said trimming and engaging the end of the post to prevent displacement of the trimming along the post.

2. A tubular furniture or like post having an end portion enlarged in cross-sectional dimension relative to the corresponding dimension of the adjacent portion of the post, and a self-retaining separate annular end trimming fitting snugly over and shaped longitudinally to conform to the shape of said enlarged post end and adjacent post portion, whereby said trimming is locked to the post against endwise removal from such post end, and an inwardly rebent integral flange part on said trimming fitting inside of said enlarged post end for preventing displacement of the trimming along the post.

3. In combination, a tubular furniture or like post of predetermined cross-sectional shape, and a trimming for one end of said post comprising a collar having an inner end portion fitting snugly over and conforming to the cross-sectional shape of said post, and an outer end portion of a different cross-sectional shape, a part of said outer end portion being of a greater cross sectional dimension than the normal corresponding dimension of said post, the latter having its end portion spread outwardly within said enlarged trimming portion to prevent removal of said collar from the end of the post, and means for preventing displacement of said collar along the post.

4. In combination, a tubular furniture or like post of predetermined cross-sectional shape, and a trimming for one end of said post comprising a collar having an inner end portion fitting snugly over and conforming to the cross-sectional shape of said post, and an outer end portion of a different cross-sectional shape, a part of said outer end portion being of a greater cross sectional dimension than the normal corresponding dimension of said post, the latter having its end portion spread outwardly within said enlarged trimming portion to prevent removal of said collar from the end of the post, and an inwardly rebent ear formed integral with

said collar for engaging a part of the post to prevent displacement of said collar along the post.

5. A tubular furniture or like post having an end portion enlarged in cross-sectional dimension relative to the corresponding dimension of the major portion of the post, and a self-retaining separate annular end trimming having an outer portion fitting 10 snugly over and shaped longitudinally to conform to the shape of said enlarged post end and adjacent post portion, said trimming being rebent so as to provide an annular flange substantially parallel to said outer 15 portion and bearing against the lower end of said post so as to prevent upward displacement of said trimming on the post, said trimming being retained against downward displacement on the post by the close conformity 20 of said outer portion thereof against the post.
